UNITED STATES PATENT OFFICE.

EDWARD MILLER, OF HOMESTEAD, PENNSYLVANIA.

CLOTHES-LINE HOOK.

No. 835,971.

Specification of Letters Patent.

Patented Nov. 13, 1906.

Application filed February 20, 1906. Serial No. 302,113.

To all whom it may concern.

Be it known that I, EDWARD MILLER, a citizen of the United States of America, residing at Homestead, in the county of Allegheny and State of Pennsylvania, have invented certain new and useful Improvements in Clothes-Line Hooks, of which the following is a specification, reference being had therein to the accompanying drawings.

10 This invention relates to certain new and useful improvements in clothes-line holders; and the invention has for its object to provide a novel form of hook for clothes-lines which will retain the line in a taut condition 15 while clothes are suspended therefrom.

Another object of this invention is to provide a clothes-line holder by which a line may be detachably connected, the holder being constructed whereby it can be easily and 20 quickly manipulated to retain a clothes-line in a taut condition.

A further object of this invention is to provide a clothes-line holder which will be extremely simple in construction, strong and 25 durable, and comparatively inexpensive to manufacture.

With the above and other objects in view, which will more readily appear as the nature of the invention is better understood, the 30 same consists in the novel construction, combination, and arrangement of parts to be hereinafter more fully described and claimed, and referring to the drawings accompanying this application like numerals of reference 35 designate corresponding parts throughout both views, in which—

Figure 1 is a perspective view of my improved clothes-line holder, and Fig. 2 is a side elevation of the same.

40 To put my invention into practice, I construct my improved clothes-line holder of a body portion 1 and a resilient pivoted arm 2, to which the end of a clothes-line 3 is detachably connected.

45 The body portion of the clothes-line holder comprises a metallic plate 4, having screw-openings 5 5, whereby the plate may be secured to the side of a building, a post, or fence

by screws, nails, or the like fastening means. The plate is provided with an outwardly-extending support 6, the end of which is provided with an upwardly-extending post 7. The support beneath the post is provided with a lug 8, which is adapted to support the resilient arm 2 when in a lowered position. 55 The post is provided with outwardly-extending pins 10 10 on its one side.

The resilient arm 2 is pivotally connected to the support 6 by a pin 11. The arm is preferably made of sheet-steel, which is 60 twisted and bent to form a hook-shaped end 12.

In practice the end of the clothes-line 3 is provided with a loop 15, which is placed in engagement with the hook-shaped end 12 of 65 the arm 2, at which time the clothes are placed upon the line 3. After the clothes have been suspended thereon the pivoted resilient arm 2 is moved upwardly and slightly sprung outwardly until it passes the 70 pins 10 10 of the post 7, when it is permitted to recede and engage behind said pins. The position of the resilient arm 2 in an elevated position is illustrated by dotted lines in Fig. 2 of the drawings, where it will be observed 75 that the arm may be supported in two positions. The positioning of the arm as shown in Fig. 2 retains the clothes-line in a taut condition and prevents the clothes suspended from the line from engaging the ground and 80 becoming soiled.

The novel construction which I have employed in connection with my improved holder permits of the clothes being easily placed in engagement with the clothes-line, 85 after which operation the arm can be swung upwardly to hold the line and the clothes in an elevated position.

Such changes in the construction and operation of my improved clothes-line holder as 90 are permissible by the appended claim may be resorted to without departing from the spirit and scope of the invention.

What I claim, and desire to secure by Letters Patent, is—

95 A clothes-line hook comprising a support-

ing-plate, an arm projecting outwardly from said supporting-plate, provided at its outer end with a vertically-extending arm, a lug on the bottom of said vertically-extending arm, 5 a plurality of fixed pins extending outwardly from said vertical arm, and a resilient hook-shaped member pivotally mounted on said first-named arm, said hook-shaped mem-

ber adapted to rest upon the said pins, or said lug, substantially as described.

In testimony whereof I affix my signature in the presence of two witnesses.

EDWARD MILLER.
